UNITED STATES PATENT OFFICE.

ROBERT S. BOLGER, OF RICHMOND HILL, NEW YORK, ASSIGNOR TO INTERNATIONAL MOTOR COMPANY, OF NEW YORK, N. Y., A CORPORATION OF DELAWARE.

TRUCK BODY.

Application filed November 24, 1920. Serial No. 426,122.

To all whom it may concern:

Be it known that I, ROBERT S. BOLGER, a citizen of the United States, residing in Richmond Hill, in the borough of Queens, 5 of the city of New York, in the State of New York, have invented certain new and useful Improvements in Truck Bodies, of which the following is a specification, reference being had to the accompanying drawings, forming a part hereof.

In the development of the motor truck business various types of truck bodies have grown into general use in different fields and can now be accepted as generally standardized. The motor truck manufacturer must meet the requirements of these many different fields and stand ready to provide truck bodies of any one of these standard types. Thus far no single body filling several fields of usefulness has been provided. The expense of manufacturing a different body for each use is burdensome to the manufacturer, since a large stock must be kept in hand and, indeed, the requirement 20 of a different body for different uses is entirely unsatisfactory to the user since his field of activity may be very broad. Among the most common standard types of body which have come into general use might be 25 mentioned the regular dumping body of the box type, with or without stakes, the express body, with or without stakes, the hay-rack body, the pipe or steel body, the stake body, the platform body and the transport 30 body. It is the object of the present invention to provide a body which shall be of universal character and of such construction that it can be converted from one of these several types into another by a driver 35 with comparatively little effort and loss of time. By the improved construction, a condition will be created wherein the manufacturer need keep in stock only one type of body while the user will always have 40 available a body which can be adapted to any requirements in widely diversified fields of trucking. A further object of the invention is to provide such an improved body which shall be of simple, rugged and inexpensive construction, readily manipulated 45 for conversion from one type to another and which shall meet all practical requirements of a satisfactory body, both from the standpoint of the manufacturer and the 50 user. The invention will be described in de-

tail in connection with the embodiment shown in the accompanying drawings, wherein:

Figure 1 is a view in side elevation of the improved body. 60

Figure 2 is a view in rear elevation of the body shown in Figure 1, one of the sections of the sides being inclined and one-half of the tail-gate being removed to show the interior of the body. 65

Figures 3-8 are diagrammatic illustrations of several forms which the body can be converted into by comparatively simple manipulation of the improved elements entering into its structure. 70

The chassis *a* of the vehicle carries thereon supporting sills *b* for the vehicle body across which extend body bolsters *c* which project well beyond the vertical sides of the box body and are preferably recessed at *c'* 75 for a purpose which will appear. Each side of the body proper is made up of a longitudinal lower section *d*, hinged along its lower edge, as at *e*, to the floor *f* of the body. To the lower section *d* is hinged an upper longitudinal section *g*. The hinge connection between these two sections *d* and *g* can be effected conveniently by securing to the outer side of the section *g* a plurality of hinge members *g'* which extend below the 80 lower edge of the section *g* and carry hinge pins *g*² which extend through co-operating hinge members *d'* carried on the outer face of the lower section *d*. The invention is not to be limited to the particular type of 85 hinge joint between the two sections *d* and *g*, although it will be appreciated that it is desirable to have a hinge joint which, while holding the sections against relative longitudinal movement, will permit the two sections to be readily disengaged from one another for reasons which will appear. In the 90 illustrated embodiment it is proposed to hold the hinge pins *g*² removably against withdrawal from the co-operating hinge sections *d'* by means of cotter pins *g*³ or the like. Extending through the lower section *d* adjacent its upper edge and, preferably in line with the respective hinge members *g'*, are several stake sockets, indicated in 95 dotted lines at *d*² (Figure 2), while along the upper edge of the lower section *d*, at suitable intervals, are formed other stake sockets *d*³. Along the upper edge of the 100 upper section *g* are formed at suitable in-

tervals several stake sockets g^4 . To the floor f of the body adjacent the rear end can be secured detachably suitable posts h , h' for the tail-gate i , the latter being of any approved form and not material to the invention. It will be seen from Figure 2 that the tail-gate i may carry hasps i' , i'' which will co-operate with eyes g^5 , d^4 , respectively, to hold the sections d , g in vertical positions. The posts h , h' may have engaged therewith chains h^2 which engage the upper sections g , to hold them in inclined relation to the lower sections d .

Having now described a suitable structure by which a universal body of the improved type can be built up, the manner of employing this structure for bringing about the ready conversion of the body from one type to another will be pointed out. The most ordinary body may be the box type. In the improved construction this will be formed by securing the lower sections d , g , at each side of the body in vertical alignment, as by means of the hasps i' , i'' , and co-operating eyes g^5 , d^4 provided at opposite sides of the tailgate i . This box body, if desired, may have its effective height increased by using stakes k at the opposite sides. These stakes can be slipped into the stake sockets g^4 in the upper edges of the upper sections g . With the stakes k removed the box body can be readily formed into a transport body by inserting the ends of posts K into the sockets g^4 and supporting the canvas over the posts, as is usual in such types. To form what is termed an express body the upper side sections g are dropped into the angular relation to the lower sections d , indicated at the left hand side of Figure 2. The chains h^2 will hold these upper sections g in their inclined positions. This express body may have its effective height increased by the use of stakes, and one feature of the present invention resides in the provision of novel forms of stakes adaptable for use with the box body and also adaptable for use with the express body and so formed as to extend vertically in either case. In order to accomplish this the improved stakes k are formed with inclined sections k' adjacent their ends, the angular relation between the stakes k and their inclined ends k' being similar to the angular relation between the upper section g and the lower section d when an express body is formed. Ordinarily this angular relation will be 45° . If it is desired to use the body as a hayrack the stakes k will have their ends k' inserted into the sockets g^4 in such manner as to support the stakes in horizontal position, as illustrated in Figure 6. The express body is the type employed with the stakes in this relation to form a hayrack. The express body with the stakes k extending vertically,

as heretofore described, is illustrated in Figure 8. If now a pipe or steel body is needed, the tailgate posts h , h' may or may not be removed, but at all events the cotter pins g^3 are withdrawn so as to permit the upper longitudinal section g to be disengaged from the hinged connection with the lower sections d . The lower sections are then swung outwardly and downwardly on their hinges until they rest on the recessed ends c' of the bolsters c . The upper sections g are then engaged with the lower sections, respectively, by passing the hinge pieces g^1 into the stake sockets d^2 , the parts assuming the relation shown in Figure 3. Pipe or steel of great length can then be laid on the body since its length is not limited by the front wall and tailgate. Upon disengaging the upper sections g from the lower sections d , in their relation to Figure 3, a plain platform body of great width will be left. The front wall l of the body can be made removable if desired. Figure 7 shows a platform body with the front wall removed. This platform body is of improved construction, since it satisfies one of the most ordinary requirements of a platform body in that it has great width. This width is obtained in converting the body in the manner described.

The upper sections g , when entirely removed, are slid under the bolsters c and rest on transverse body sills b' , being conveniently held against withdrawal by means of pivoted latch pieces m carried by one of the bolsters c . The platform body thus formed may have the stakes k engaged with the lateral stake sockets d^2 along the edge of the sections d , the resulting body being indicated conventionally in Figure 5.

In the illustrated embodiment, the substructure of the entire body is hinged as at n on the chassis a , while the forward end is connected through an arm m' and hoisting cable m^2 to a power operated dumping device m^3 whereby the body becomes a dump body. This naturally widens the field of usefulness of the improved body, but it is to be understood that the convertible features may be incorporated in a single body wherein there is no provision for dumping.

The entire structure described enables a single body to be built by a manufacturer and converted by the purchaser into one of the several standard types now commonly required in the different trucking fields. The advantages have been pointed out and their value to the art will be evident.

I claim as my invention:

1. In combination with a chassis, a floor for a body mounted thereon, sides for the body comprising longitudinal lower sections, hinged to the floor, and longitudinal upper sections, hinged removably to hinge members on the lower sections, means to secure

the upper and lower sections at a point below the meeting edges of the sections in vertical alinement, means to maintain the upper sections in inclined relation to the lower sections, and means to support the lower sections in prolongation of the floor when the upper sections are removed.

2. In combination with a vehicle chassis, a floor for a body supported thereon, longitudinal lower side sections hinged to the floor, longitudinal upper side sections hinged on the lower side sections at a point below the meeting edges of the sections, the lower side sections being provided with stake sockets along their upper edge and along their inner walls adjacent said upper edge, and said upper longitudinal sections being provided with stake sockets along their upper edge, and stakes having inclined portions at one end and adapted to have either end engaged with all of said sockets when said side sections are moved to expose the sockets.

3. In combination with a vehicle chassis, transverse bolsters carried thereon and extending beyond the sides of the vehicles, a floor supported on the bolsters, lower longitudinal side sections hinged to the floor, upper longitudinal side sections removably hinged on the lower side sections, a tail-gate supported at the rear end of the body, posts removably secured to the floor for the support of said tail-gate, means to secure the upper and lower side sections in vertical alinement to form a box body, means to maintain the upper side sections in angular

relation to the lower side sections to form an express body, said lower side sections being movable into positions of rest on the extensions of said bolsters and in prolongation of the floor when the upper side sections are removed.

4. In combination with a vehicle chassis, a floor body supported thereon, longitudinal lower side sections hinged to the floor, upper longitudinal sections resting on the lower sections and carrying hinge elements extending beyond the lower edges of the upper sections, co-operating hinge elements on the lower sections engaged by said first named hinge elements at a point below the meeting edges of the section, said hinge elements being disconnectible to permit the removal of the upper longitudinal sections, and means to support the lower sections in prolongation of the floor, said lower sections being formed with sockets in their inner wall adjacent their edges to receive said first named hinge elements and support the upper sections in vertical position when the lower sections are in horizontal position.

5. A stake for a convertible truck body having a long body section, a short section inclined with relation to the body section, the ends of either section being adapted to engage with the stake sockets in the truck body.

This specification signed this 22d day of November, A. D. 1920.

ROBERT S. BOLGER.
